UNITED STATES PATENT OFFICE.

HENRY CLAY WHITMARSH, OF BROOKLYN, ASSIGNOR TO CHARLES C. CARPENTER, OF NEW YORK, N. Y.

DESIGN FOR SUSPENDERS.

SPECIFICATION forming part of Design No. 17,085, dated February 1, 1887.

Application filed November 8, 1886. Serial No. 218,345. Term of patent 7 years.

To all whom it may concern:

Be it known that I, HENRY CLAY WHITMARSH, a citizen of the United States, residing at Brooklyn, in the county of Kings and State of New York, have invented certain new and useful Improvements in Designs for Suspenders; and I do declare the following to be a full, clear, and exact description of the invention, such as will enable others skilled in the art to which it appertains to make and use the same, reference being had to the accompanying drawing, and to the letters and figures of reference marked thereon, which form a part of this specification.

15 My invention relates to designs for shoulder-braces, consisting, essentially, of two principal parts joined by a lacing.

The invention is illustrated in a single figure, which is a face elevation.

20 The leading feature of my design consists in a two-part back plate, each part of which is shown as forming part of their respective webs, and a lacing which is represented as connecting the said half-plates.

25 Referring to the drawing, A designates one web of a suspender, and B the other web. A' and B' designate their respective back plates. Each part of the back plate is formed with a straight side, the side opposite to which di-

verges from a straight line, as shown, and with 30 diamond-shaped ends. Each part of the plate is ornamented with a plurality of holes, and the two halves, when in use, are arranged with their straight sides contiguous, and further ornamented by cross lines C, representing a lacing, as shown.

What I claim is—

1. In a design for shoulder-braces or suspenders, the two-part back plate having contiguous sides ornamented with a series of holes 40 and cross-lines, C, and with outer curved sides, each part of the back plate being further provided or ornamented with webs extending from opposite ends in lateral directions, as shown.

2. In a design for shoulder-braces or suspenders, the design for the back plate herein set forth, consisting of a two-part plate having the two halves of said plate provided with straight contiguous sides, diamond-shaped top and bottom, and their outer sides inwardly 50 curved and ornamented with a series of holes and cross-lines, C, as shown and described.

In testimony whereof I affix my signature in presence of two witnesses.

HENRY CLAY WHITMARSH.
